UNITED STATES PATENT OFFICE.

DANIEL E. MCNICOL, OF EAST LIVERPOOL, OHIO.

DESIGN FOR AN EARTHENWARE COFFEE-POT.

SPECIFICATION forming part of Design No. 13,340, dated October 17, 1882.

Application filed September 6, 1882. Term of patent 3½ years.

To all whom it may concern:

Be it known that I, DANIEL E. MCNICOL, of East Liverpool, in the county of Columbiana and State of Ohio, have invented and produced a new and original Design for Earthenware Coffee-Pots, of which the following is a specification, reference being had to the accompanying drawings, forming part thereof.

Figure 1 is a side elevation. Fig. 2 is a vertical section, (these two views being deemed necessary to fully illustrate the design.)

The design consists in the formation of the body of the pot in the shape shown, with a spout and handle, and a lid hinged to the top flange, as shown and described.

The leading features of this design consist in the round tapering body of the pot, having a smooth surface, the base consisting of a light ogee bead or mold, and the top edge terminating in a flaring flange. At one side of said body is attached a handle in the form of a

horn, having sides roughened or impressed with an imitation of the surface of a buck-horn at or near the top curve of the handle. Opposite said handle is made a pitcher-spout representing a leaf. The top portion of said spout is partly covered. The lid consists of a truncated cone surmounted with an acorn.

Referring to the drawings, A is the body of the pot. B is the handle; C, the spout, and D the lid.

Having described my invention, I claim—

The design for an earthenware coffee-pot herein shown and described, consisting of the tapering body A, having flaring flange at top 35 and a handle and spout in the pattern described, and a lid hinged to the flange, all as described and represented.

DANIEL E. MCNICOL.
